UNITED STATES PATENT OFFICE.

HAROLD A. SIMMS AND JOHN H. SHARP, OF CHICAGO, ILLINOIS.

REFRIGERATOR CAR.

Application filed November 24, 1924. Serial No. 751,894.

Our invention relates to improvements in refrigerator cars, and is particularly concerned with the provision of a refrigerator car having a bulkhead for forming the ice chamber or compartment, the bulkhead being constructed in such a manner that it can be moved out of operative position for the purpose of converting the ice chamber or compartment space into loading space.

10 The objects of our present invention are: First, to provide a refrigerator car, of the character described, comprising a bulkhead that can be easily and quickly moved into inoperative position so as to make the ice chamber space available for loading;

Second, to provide a refrigerator car comprising a bulkhead which, while being moved to its inoperative position, protects the workmen from falling ice;

20 Third, to provide a refrigerator car comprising an ice hatchway, a bulkhead and means for closing the hatchway when the bulkhead is moved to inoperative position, so as to prevent pilferage of the car through the ice hatchway;

Fourth, to provide a refrigerator car, such as described, in which the pilferage-preventing device is automatically moved to its closed position when the bulkhead is moved 30 to its inoperative position;

Fifth, to provide a refrigerator car, of the character described, in which down draft hoods are formed in the pilfer plate and in which the pilfer plate moves to a position 35 above the upper edge of the bulkhead when the latter is moved to operative position, so as not only to cause circulation of the air through and around the ice, but further to prevent pilferage of the car through the space above the bulkhead and the hatchway;

Sixth, to provide a bulkhead comprising means that will permit easy inspection of the well or sump beneath the ice grate;

Seventh, to provide a construction, such 45 as described, in which the ice grates are removably mounted and constructed so as to drop into the well where they will be out of the way in loading the car, and where they will act to protect the metal lining of the well;

Eighth, to provide a refrigerator car, such as described, comprising a bulkhead that is comparatively light in weight but strong enough to withstand the rough usage to

which it is subjected, and which, at the same time, will not conduct frost to the loading space; and

Ninth, to provide a refrigerator car of the character described, that is simple in construction, economical to manufacture and in which the bulkhead is easily movable into and out of its operative position.

Other objects of our invention will appear as this description progresses, reference being had to the accompanying drawing, in which—

Figure 1 is a vertical, transverse section through a refrigerator car embodying our invention;

Figure 2 is a vertical, longitudinal section 70 taken on line 2—2 of Figure 1;

Figure 3 is a sectional detail taken on line 3—3 of Figure 2, showing some of the means for supporting the ice grate and certain features of construction of the bulkhead, portions of the latter being broken away for the purpose of better illustration;

Figure 4 is a sectional detail, on an enlarged scale, taken on a line corresponding to line 4—4 of Figure 1;

Figure 5 is a sectional detail taken on line 5—5 of Figure 2;

Figure 6 is a section through the ice hatchway, showing a modified form of a portion 85 of our invention;

Figure 7 is a view similar to Figure 1, showing a modified form of our invention, portions of the bulkhead and well screen being broken away;

Figure 8 is a longitudinal section taken 90 on line 8—8 of Figure 7;

Figure 9 is a view similar to Figure 8, but showing the bulkhead in its inoperative position;

Figure 10 is a horizontal section taken on 95 line 10—10 of Figure 7;

Figure 11 is an enlarged sectional detail taken on line 11—11 of Figure 7; and

Figure 12 is a sectional detail taken on 100 line 12—12 of Figure 9.

Throughout the several views similar reference characters are used for referring to similar parts and the sections are taken looking in the directions of the small arrows.

Referring to the drawings, and, for the 105 time being, to Figures 1 to 5, inclusive, we have illustrated our invention as being embodied in a refrigerator car comprising the

sides 10, the top 11 and floor 12, portions of which are shown in section, and also an end wall 13 that is shown in section. The construction of the sides, top, bottom and end walls may be in accordance with standard or conventional design, and further description thereof is thought to be unnecessary. Adjacent one end of the car and above the space that is to form the ice chamber or compartment, we provide an ice hatchway 14 through which ice can be supplied to the ice chamber 15.

For the purpose of confining the ice to the ice chamber or compartment, we provide two bulkhead doors B that are pivotally mounted on opposite sides of the car, as shown at 16, so that they may either be swung into position across the car, as shown in Figures 1 and 2, or swung into position along the 20 sides of the car so as to be out of the way and to permit the ice compartment to be used as loading space.

Each of the bulkhead doors comprises a rectangular frame formed of channel iron 17 for confining the edges of the wooden facing 18 that contacts with the lading to prevent damage through contact with frost or rust.

A sheet of metal 19, the edges of which 30 are confined within the frame formed by the channel members 17, forms the opposite or back side of the door, and between the facing 18 and the metal sheet 19 are confined a layer 20 of suitable insulating material, such as mineral wool, cork, etc., and a series 35 of spacing strips 21 that form an air space between the layer of insulation 20 and the wooden facing 18. A plurality of vertically extending angle irons 22 are secured, 40 in spaced relation, to the back side of each of the bulkhead doors, as shown in Figures 2, 3 and 4. The outwardly extending flanges of these angle irons act as supports for a screen 23, or other suitable reticulated partition that may be held in place by means of 45 clamping strips 24, or in any other desired manner.

For the purpose of further strengthening the doors and preventing them from sagging, we prefer to provide each of them with 50 two or more transversely extending metal strips or bars 25 and 26. For locking the doors in their operative position, we provide one of them with a cam plate 27 and 55 the other with a locking bar comprising a short section of shafting 28 that is rotatably mounted in the brackets 29 and which carries, at its inner end, an eccentric pin 30 that can be moved into contacting relation 60 with the bottom of a recess 31 formed in the cam plate 27. A lever 32 is secured to the shaft 28 and is provided, at its free end, with an open or ring-shaped handle 33 that is adapted to pass over interlocking ring-shaped lugs 34 and 35 formed on the adjac-

ent ends of the two lower bars 26. These lugs are provided with registering openings through which can be dropped a pin 37 for holding the handle, and consequently the lever 32, in its locked position. When it is 70 desired to open the bulkhead doors, by pulling outwardly on the handle 33, the operator can cause the eccentric pin 30 to engage the top of the recess 31 in the cam plate 27, and thus pry the one door outwardly, whereupon both of them can be easily moved to their inoperative positions.

We prefer to provide additional means for holding the bulkhead doors in their closed position, and for this purpose we provide 80 two comparatively heavy brackets 38 that extend upwardly from the tops of the doors and are adapted to contact with stops 39 secured to the top of the car. These stops comprise lugs 40 that are adapted to 85 be received by suitably formed openings in the upper ends of the brackets 38. These lugs have transversely extending openings for receiving cotter pins 41, or other suitable means for securing the upper ends of 90 the brackets 38 to the stops 39.

For supporting the ice in the ice chamber above the well 42, we provide an ice rack comprising bars 43 that are held in spaced relation by means of suitable spacers 44, or 95 clamped together by means of long rods or bolts 45. The grate thus formed is supported by a channel iron shelf 46, extending across the end of the car and along the sides to a point adjacent the bulkhead doors. We 100 also secure to the inner face of the bottom channel member 17 of each bulkhead door an angle iron 47, the horizontal flange of which acts as a support for the edge of the ice grate adjacent the bulkhead. When the 105 bulkhead doors are moved back to their inoperative position, the ice grate may be removed from its supporting shelf and dropped into the well, as indicated in dotted outline in Figure 2.

To permit easy access to the well for the purpose of inspection and for the purpose of cleaning the trap 48, we provide a screen 49 for each of said bulkhead doors. These screens are carried by suitable frames 50 115 that are pivotally mounted on the lower ends of the doors B, as shown at 51. From this description it will be apparent that the lower ends of the screens can be turned outwardly and upwardly to permit access to 120 the well. The well is usually lined with sheet metal, or other suitable water proof material, but illustration of this feature has been omitted for the purpose of clarity.

A pair of horizontally extending rods or 125 shafts 52 extend across the top of the car in substantially parallel relation to the plane of the bulkhead and are supported by suitable bearing blocks or brackets 53 secured to the top or roof of the car. Pilfer plates 130

54 are pivotally mounted upon the rods 52 and are adapted to swing down to the position shown in Figures 1 and 2 when the bulkhead doors are in their operative positions. 5 Adjacent their upper ends the pilfer plates 54 are slotted and pressed outwardly to form down draft suction hoods 55 that assist in producing a circulation of air down over the ice and through the car.

10 The pilfer plate 54 is provided for the purpose of closing the ice hatchway 14 when the bulkhead doors are swung back to their inoperative position, and we prefer to accomplish the closing of these pilfer plates 15 automatically. This we accomplish by means of the cable 56 that passes around the sheaves 57 and 58 and has one end attached to the pilfer plate, as shown at 59, and the other end attached to the top 20 of the corresponding bulkhead door, as shown at 60. It will be seen that when the bulkhead doors are moved to inoperative position along the sides of the car, the pilfer plates will be drawn upwardly to the 25 positions shown in dotted outline in Figure 2, and thus close the hatchway or hatchways. For further securing the pilfer plate in its operative position, we prefer to provide the supporting pins 61 that are received 30 by openings 62 in the pilfer plate. Keys 61' can then be inserted in suitable openings in the pins 61 and thus support the pilfer plate.

If desired, the combined down draft device and pilfer plate described above may be omitted and a pilfer plate 54', of the type shown in Figure 6, may be substituted therefor. This pilfer plate is not automatic in its operation, does not include any down 40 draft device and is provided merely for the purpose of closing the hatchway 14 when the bulkhead doors are moved into their inoperative position.

From the above description it will be apparent that when the bulkhead doors are 45 in the positions shown in Figures 1 and 2, and the ice chamber or compartment, formed by the bulkhead doors and the sides and end of the car, and also by the ice grate, 50 is substantially filled with ice, the pilfer plates 54 will be held in the position shown in Figure 2, so that it will be impossible for anyone to gain access to the loading space of the car through the hatchway 14 and the 55 space above the bulkhead doors. It will also be seen that the down draft suction hoods 55 and the spaces between the screens 23 and the metal plates 19 will induce a circulation of air down through and around the ice that 60 will greatly expedite the cooling of the car and its contents. It will also be seen that by providing bulkhead doors in which wood, or some other non-conducting material is used as a facing on the side toward the loading 65 space, we have provided a construction

that will prevent injury to the contents of the car by frost that might otherwise be conducted to the contents if the face of the door were made of metal or other frost conducting material. It will also be seen that 70 the provision of the pivoted screen 49 not only permits the circulation of the air through the car, but also permits ready access to the ice well.

When the bulkhead doors are moved back 75 to their inoperative positions, in order to convert the ice chamber or compartment into loading space, the pilfer plates are moved up into their inoperative positions so as to prevent anyone from entering the car 80 through the ice hatchways. When the doors are in their inoperative positions, the ice grate can be removed and dropped down into the well, as heretofore described, where it will protect the metal lining of the well 85 against injury.

In the modified form of our invention, illustrated in Figures 7 to 12, inclusive, the bulkhead in place of being divided in two parts, pivotally mounted upon opposite 90 walls of the car, is formed in a single part, or unit, that is adapted to be moved into a position adjacent the end of the car so as to occupy a minimum space. In this form of our invention we provide means for preventing pilferage of the car through the hatchway and make use of a part of the bulkhead for protecting the well pan.

In this form of our invention the bulkhead comprises a rectangular frame 65, 100 formed of channel iron, the rear end of which is closed by a sheet metal plate 66 and the opposite end of which is closed by suitable wooden sheathing 67. Confined between the plate 66 and the sheathing 67 is a layer 105 68 of mineral wool, cork, or other suitable heat insulating material. Vertically extending angle irons 69 are secured to the inner end or face of the bulkhead by means of bolts 70, or in any other desired manner, 110 and support the woven screen 71 in spaced relation to the metal sheet 66. This screen is held in place by means of the metal strips 72 that are held in place by means of bolts 73 fastened through the flanges of the angle 115 irons. A leg 74 supports each end of the bulkhead and is in turn supported by a roller 75 that is adapted to roll upon the bottom of the car and preferably upon a metal strip 76 provided for that purpose. 120 A bracket, or upright, 77 extends upwardly from each end of the bulkhead and carries, at its upper end, a roller 78 adapted to ride in a channel iron 79 secured to the roof of the car and extending transversely of the 125 car.

A pilfer plate 80 is pivotally mounted on the uprights 77. This pilfer plate has down draft hoods 81 formed therein, similar to those described in connection with the em- 130

bodiment of our invention shown in Figures 1 to 6, inclusive. Eye bolts 82, carried by the frame of the bulkhead, extend through suitable openings in the lower edge of the 5 pilfer plate, so that pins or keys 83 may be used for locking the pilfer plate in the position shown in Figure 8, thereby preventing anyone from gaining access to the car by swinging the pilfer plate to an open position.

An ice well screen, comprising the vertically extending angles 84 and the transversely extending spaced angles 85, is pivotally mounted upon the lugs 86, one of which 15 projects outwardly from each end of bulkhead. Removable pivot pins 87, extending through one of the flanges of each angle 84 and the adjacent lug 86, provide means for pivotally mounting the ice well screen but 20 permit the ready detachment of the screen from the bulkhead for a purpose that will later be referred to.

An ice rack, comprising the longitudinally extending angles 88 and the transversely extending angle 89, upon which are supported the wooden bars 90, is pivotally mounted upon the sides of the car by means of the 25 pivot pins 91, so as to permit it to be swung upwardly to the position shown in Figure 9. 30 An angle iron 92, carried by the bulkhead, forms a support for the free end of the ice rack when it is in the position shown in Figure 8. Preferably, the angle iron 92 is supported by bolts 93 that can be removed 35 so as to permit the angle iron 92 to drop. This allows the free end of the ice rack to drop downwardly to discharge whatever ice 40 may be resting thereupon through the space below the bulkhead.

40 For the purpose of moving the ice rack to a position that will enable it and the bulkhead to be moved to the position shown in Figure 9, we provide the lever 94 that is pivotally mounted upon one side of the car, as shown at 45 95, and provided with a projection 96 that extends below the adjacent longitudinally extending angle iron 88. The lever projects outwardly between the frame members of the bulkhead and the side 50 of the car and carries a foot plate 97 upon which the operator can step to lift the ice rack into such angular position that when pressure is applied to the bulkhead it and the ice rack can be moved to the position 55 shown in Figure 9. Preferably, the foot plate 97 is pivotally mounted upon the outer end of the lever 94 so that it can be swung up against the side of the car. If desired, another similar lever can be mounted upon 60 the opposite side of the car.

When the bulkhead is collapsed to the position shown in Figure 9, the pilfer plate is swung upwardly to the position shown in the same figure, and held in place by 65 means of an eye bolt 98 and a key 99, or in

any suitable manner. The space left between the edge of the pilfer plate and the adjacent side of the hatchway 14' is too small to permit a person to enter the car through this space. When the bulkhead has 70 been moved to the position shown, the pins 87 are withdrawn, thus permitting the well screen to be dropped into the well pan, as shown in Figure 9, thereby providing loading 75 rack for the merchandise and at the same time protecting the well pan.

The walls of the car that form the other sides of the ice chamber are preferably provided with uprights 100, to which is secured sheets 101 of metal screen. This provides 80 passageway for the circulation of the air.

The pilfer plates, in either their closed or opened position, and irrespective of whether the bulkhead is in its operating or collapsed 85 position, can be used to convert the refriger- 85 ator car into a ventilator car during cool weather when the car requires no ice.

A further advantage of our present construction is that the collapsible bulkhead permits access to the end of the car for making 90 repairs without the necessity of destroying or removing the bulkhead. This is of special importance in that the common type of built-in bulkhead must be torn out entirely in order to make repairs at the end of the 95 car. The cost of tearing out a bulkhead of the conventional type and later rebuilding it is greater than the original cost of building such bulkhead, and for that reason our construction is of particular importance. 10

While we have described the details of construction of the preferred embodiments of our invention, it is to be clearly understood that our invention is not limited to these details, but is capable of other adaptations and modifications, within the scope of the appended claims. 10

Having thus described our invention, what we claim is:

1. The combination with a car having an 11 ice hatchway adjacent one end thereof, of a pair of bulkhead doors pivotally mounted on opposite sides of said car and movable into positions along the sides of said car, or into 11 positions to form a bulkhead across said car, a well screen pivotally supported on the lower end of each of said doors, a pilfer plate pivotally mounted over each of said doors to turn about a horizontal axis, said pilfer plate comprising a plurality of down draft 12 suction hoods, and means actuated by said doors for moving said pilfer plates across the lower side of said hatchway when said doors are moved to a position along the sides of said car.

2. The combination with a car having an ice hatchway adjacent one end thereof, of a pair of bulkhead doors pivotally mounted on opposite sides of said car and movable into positions along the sides of said car, or 13

- into positions to form a bulkhead across said car, a well screen pivotally supported on the lower end of each of said doors, a pilfer plate pivotally mounted over each of said doors to turn about a horizontal axis, and means actuated by said doors for moving said pilfer plates across the lower side of said hatchway when said doors are moved to a position along the sides of said car.
3. The combination with a car having an ice hatchway adjacent one end thereof, of a pair of bulkhead doors pivotally mounted on opposite sides of said car and movable into positions along the sides of said car, or into positions to form a bulkhead across said car, a well screen supported on the lower end of each of said doors, a pilfer plate mounted over each of said doors to turn about a horizontal axis, said pilfer plate comprising a plurality of down draft suction hoods, and means actuated by said doors for moving said pilfer plates across the lower side of said hatchway when said doors are moved to a position along the sides of said car.
4. The combination with a car having an ice hatchway adjacent one end thereof, of a bulkhead door pivotally mounted on one side of said car, a pilfer plate pivotally mounted above said door, and means for moving said pilfer plate across said hatchway when said door is swung to a position along the side of said car.
5. The combination with a car having an ice hatchway adjacent one end thereof, of a bulkhead door pivotally mounted on one side of said car, a pilfer plate mounted above said door, and means for moving said pilfer plate across said hatchway when said door is swung to a position along the side of said car.
6. The combination with a car, of means for forming a bulkhead across said car, comprising a door pivotally mounted on the side of the car to be swung to a position across said car, down draft means pivotally mounted to swing on a horizontal axis above said door when said door is in its operative position and extending substantially across said door, and a well screen pivotally mounted on the lower end of said door.
7. The combination with a car, of means for forming a bulkhead across said car, comprising a door pivotally mounted on the side of the car to be swung to a position across said car, down draft means pivotally mounted to swing on a horizontal axis above said door when said door is in its operative position and extending substantially across said door.
8. The combination with a car, of means for forming a bulkhead across said car, comprising a door pivotally mounted on the side of the car to be swung to a position across said car, a down draft device mounted above said door when said door is in its operative position and of substantially the same width as the door, and a well screen pivotally mounted on the lower end of said door.
9. The combination with a car, of means for forming a bulkhead across said car, comprising one member pivotally mounted to swing about a vertical axis and another member pivotally mounted to swing about a horizontal axis.
10. The combination with a car, of a door movable to a position across said car and a down draft device mounted to move into position above said door, said down draft device having means for co-acting with the ice behind said door for holding said down draft device in position to prevent pilferage through the space above said door.
11. The combination with a car, of a bulkhead door pivotally mounted on one side of said car, co-acting ice grate supports carried by said car and said door, an ice grate removably supported by said supports, and a member pivotally mounted on the lower end of said door for permitting access to the space below said ice grate.
12. A bulkhead door for a refrigerator car comprising a rectangular metal frame, a wooden facing secured to said frame, and a metal facing secured to said frame in spaced relation to said wooden facing, heat insulating means confined between said facing, and a reticulated member supported in spaced relation to said metal facing.
13. A bulkhead for refrigerator cars comprising a pilfer plate having downwardly directed openings formed therein.
14. The combination with a refrigerator car having a hatchway and a bulkhead forming an ice chamber, of a pilfer plate pivoted to be swung into position across said hatchway or over said bulkhead, said plate having openings forming ventilating openings when said plate is positioned across said hatchway, and forming draft openings when said plate is positioned above said bulkhead.
- In witness whereof, we hereunto subscribe our names this 19 day of November, 1924.

HAROLD A. SIMMS.
JOHN H. SHARP.
